UNITED STATES PATENT OFFICE.

BERNITA LUNDY, OF SAN FRANCISCO, CALIFORNIA.

DESIGN FOR A CURTAIN PULL.

Application filed November 21, 1925. Serial No. 15,489. Term of patent 3½ years.

To all whom it may concern:

Be it known that I, BERNITA LUNDY, a citizen of the United States of America, residing at San Francisco, California, United States of America, have invented a new, original, and ornamental Design for a Curtain Pull, of which the following is a specification, reference being had to the accompanying drawing, forming part thereof.

Fig. 1 shows an elevational view of a curtain pull, showing my new design, and

Fig. 2 shows a top plan view of a curtain pull, showing my new design.

I claim:

The ornamental design for a curtain pull as shown.

Dated at San Francisco, California, this 13th day of Nov., 1925.

BERNITA LUNDY.
